UNITED STATES PATENT OFFICE.

WILLIAM S. SKELTON, OF EVANSVILLE, INDIANA.

UNION GARMENT.

Application filed September 30, 1920. Serial No. 413,768.

To all whom it may concern:

Be it known that I, WILLIAM S. SKELTON, a citizen of the United States, residing at Evansville, in the county of Vanderburgh and State of Indiana, have invented certain new and useful Improvements in Union Garments; and I do hereby declare the following to be a full, clear, and exact description of the invention, such as will enable others skilled in the art to which it appertains to make and use the same.

This invention relates to certain new and useful improvements in union garments and has for its primary object the provision of a garment of the character stated which will be composed of the minimum number of pieces of material and in which the flap may be readily secured in its closed position within the depending end of the body back of the garment by means of a strap passed through loops to hold the upper edge of the seat flap while the vertical edges thereof are connected at the side of the garment by buttons on side flap members.

The invention has for another object the provision of a garment of the character stated in which the front may be formed of a single piece slit vertically and secured together by a vertical front row of buttons or other securing devices, while the belt is formed of a lower section comprising the rear halves of the legs of the garment and the seat flap, which latter is received beneath the depending end of the upper back section, forming the back of the body of the garment and having openings in its lower portion to receive strap carrying loops formed on the outer face of the flap so that a belt may be passed through the belt loop to hold the flap in closed position and retain the lower end of the back of the body of the garment in proper position over the upper edge of the flap, means being provided for closing the vertical edges of the seat flaps at the sides of the garment forming the hip portion thereof.

The invention has for a further object the provision of a garment of the character stated in which the garment will be constructed in such a manner as to make it appear that the same is formed as a one piece garment and constructed of the minimum amount of material as well as the minimum number of pieces or sections.

With the foregoing and other objects in view as will appear as the description pro-

ceeds, the invention consists in the novel construction, combination and arrangement of cooperating elements as hereinafter more specifically described, claimed and shown in the drawings forming a part of the present application, and in which:

Figure 1 is a front elevation of the garment.

Figure 2 is a side elevation thereof.

Figure 3 is a transverse horizontal section through the waist portion of the garment, as shown on line 3—3 of Figure 2.

Figure 4 is a detail vertical section on the plane of line 4—4 of Figure 2.

Referring more in detail to the drawings in which similar reference characters designate corresponding parts throughout the several views, 1 indicates the front of the garment which is composed of a single section of material and which includes the front of the legs of the garment as well as the entire body thereof, the body being slit or separated vertically along the center, whereby the garment may be readily placed on the wearer or removed. The overlapping inner edges of the front of the garment forming closure flaps 2 which are secured together by the buttons 3 carried by one flap and extending through buttonholes on the opposite remaining flap, or by any other suitable securing means.

The back of the garment is composed of a lower section 5 forming the rear half of the legs of the garment and seat 6 at the upper ends of the leg portions at the back of the garment. The rear leg portions are adapted to be secured to the front leg portions of the garment along their inner and outer edges, as shown by rows of stitching 7. The seat flap 6 carries a plurality of belt receiving loops 8 in its outer face which are adapted to extend through openings 9 in the lower depending and overlapping portion of the upper section 10 of the rear side of the garment and which upper section forms the back of the body of the garment. A belt 11 is extended around the waist portion of the garment, outwardly of the depending end of the section 10 forming the back of the body of the garment and through the belt loops 8 of the seat flap 6 when the latter is closed, as shown in the drawings, thereby retaining the flap 6 in its closed position and preventing the lower edge of the rear body member 10 from moving out of proper position over the seat flap and leaving exposed the upper edge of

the seat flap 6. The vertical or side edges 12 of the seat flap 6 are adapted to have removable engagement and detachable engagement with the side securing flap portions 13 of the hip 5 portion of the front section 1 of the garment, as shown in Figure 1 of the drawings. Buttons and buttonholes may be employed for this connection, as shown at 14, if desired.

10 The garment may be provided with sleeves 15 secured to the front section 1 and rear upper section 10, as shown at 16 in Figure 2 of the drawings and a collar 17 may also be provided for the garment, if desired.

15 From the foregoing paragraphs taken in connection with the accompanying drawings, it will be seen that I have provided a simple form of garment which may be readily constructed from the minimum amount of material and composed of the minimum number 20 of sections. Furthermore, the flap section will be protected when in closed position and yet may be readily released after removing the belt 11.

25 While the preferred embodiment of the in-

vention has been shown and described, it will be understood that minor changes in the details of construction and arrangement of parts may be resorted to within the scope of what is claimed without departing from 30 the spirit of the invention.

What is claimed is:—

A garment having a trouser section and an upper section, said trouser section having a seat member capable of opening and overlapped by said upper section when closed, loop means on the seat member passable through the adjacent portion of the upper section, in combination with a belt separable from the section to take up the slack at the 35 waist of the garment and insertible through said loop means exteriorly of the upper section to support the trousers and close the seat section.

In testimony whereof I affix my signature 40 in presence of two witnesses.

WILLIAM S. SKELTON.
